W. A. BURKHOLDER

BATTERY TERMINAL

Filed March 28, 1924

INVENTOR
W. A. Burkholder
ATTORNEY

UNITED STATES PATENT OFFICE.

WILLIAM A. BURKHOLDER, OF JUNCTION CITY, KANSAS.

BATTERY TERMINAL.

Application filed March 28, 1924. Serial No. 702,610.

To all whom it may concern:

Be it known that I, WILLIAM A. BURKHOLDER, a citizen of the United States, residing at Junction City, in the county of Geary and State of Kansas, have invented certain new and useful Improvements in Battery Terminals; and I do declare the following to be a full, clear, and exact description of the invention, such as will enable others skilled in the art to which it applies to make and use the same, reference being had to the accompanying drawings, and to the figures of reference marked thereon, which form a part of this specification.

This invention relates to a terminal for secondary batteries and the primary object thereof is to provide a terminal fastening for the cable so that the cable can be secured to the binding post in such a manner that it may be disconnected without danger of breaking the battery cell.

Ordinarily connections are made between the cable and the binding post by placing a socketed member over the binding post and fastening it in place by a set screw. After a while the socket and binding post freeze or stick together on account of corrosion which sets up between the socket and the binding post or between the two complementary members of the connection. Then in order to disconnect the cable from the binding post, the binding post is put under severe strain resulting in its being broken off, in many instances, so that a new binding post has to be burned on.

My invention contemplates the elimination of the above mentioned difficulty and the desired result is accomplished by novel means which will be specifically referred to hereinafter, reference being had to the accompanying drawings, in which—

Fig. 1 is a perspective view of a battery terminal constructed in accordance with my invention.

Fig. 2 is a sectional view through the battery terminal showing the parts in position for making the connection.

Fig. 3 is a similar view showing the complementary members disconnected, and

Fig. 4 is a sectional view through the socket member and a securing nut for fastening it to the binding post.

The battery 1 may be of approved construction with a binding post 2 in the form

of a truncated cone with an upstanding threaded stud 3 projecting above the truncated portion of the binding post. For convenience, I may utilize a bolt with a head 4 cast in the binding post as clearly illustrated in Fig. 2. The head 4 serves as an anchor to prevent the stud from being pulled out of the binding post by the adjusting nut 5 carried by the socket member 6.

The socket member is provided with an internal conical socket or recess 7 adapted to tightly fit over the binding post 2 and it is provided with a shouldered portion or seat 8 to receive the flange 9 of the nut 5 having a polygonal portion 11 so that it may be received between the jaws of a wrench. The flange is held on its seat by a cover plate 12 fastened to the socket member 6 or the socket member can be loosely secured to the nut in any well known manner. The nut is therefore adapted to have rotative movement with respect to the socket member, therefore when the nut is screwed on the stud 3, the socket member will be forced down on the binding post to make electrical connection between the complementary members 2 and 6, the cable 14 being fastened to the socket member in the usual manner.

When it is desired to disconnect the complementary members 2 and 6, a wrench may be applied to the polygonal portion 11 of the nut 5, which upon being unscrewed will exert a straight longitudinal pull on the socket member so that even if the members 2 and 6 are stuck together by corrosion, the force will be sufficient to pull them apart because the nut and stud will act as a screw jack exerting great power and since the strain will be on the stud and on the binding post 2, no strain will be communicated to the cell, consequently liability of the cell becoming broken will be entirely eliminated.

It will be apparent from the foregoing that the connection between the cable and the binding post may be made and broken in a very convenient and expeditious manner and that liability of disruption of the battery jar or cell in making and breaking the connection will be entirely eliminated.

What I claim and desire to secure by Letters Patent is:

1. A battery terminal comprising a binding post, a socket member to fit over the binding post, a nut rotatably mounted in the

socket member and co-operating with the binding post the nut being rotatable in one direction to force the socket member longitudinally upon the binding post and rotatable in an opposite direction for forcing the socket member away from the binding post.

2. In combination, a binding post including a threaded projecting stud, a socket member having longitudinal movement with respect to the binding post, a rotative nut carried by the socket member and a cover

plate carried by the socket member to hold the nut in rotative engagement with the socket member, the nut having co-operative movement with the stud so that when it is turned in one direction, it will force the socket member in intimate contact with the binding post and when it is moved in the other direction, it will move the socket member out of contact with the binding post.

In testimony whereof I affix my signature.

WILLIAM A. BURKHOLDER.
